(57) **CLAIM**

The ornamental design for a desktop terminal for multimedia communication, as shown and described.

DESCRIPTION

FIG. 1 is a front and right side perspective view of the desktop terminal for multimedia communication, showing my new design;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a rear elevational view thereof.

The indicia shown in the figures is hereby disclaimed and forms no part of the claimed invention.
